UNITED STATES PATENT OFFICE.

ARTHUR ROBERTS, OF EVANSTON, ILLINOIS, ASSIGNOR, BY MESNE ASSIGNMENTS, TO
CHICAGO TRUST COMPANY, TRUSTEE, OF CHICAGO, ILLINOIS, A CORPORATION.

COKE OVEN.

Application filed July 11, 1919. Serial No. 309,995.

To all whom it may concern:

Be it known that I, ARTHUR ROBERTS, a citizen of the United States, residing at Evanston, county of Cook, and State of Illinois, have invented certain Improvements in Coke Ovens and the like, of which the following is a specification.

The present invention has to do with improvements in coke ovens and like structures. The invention has particular reference to the construction of heating walls, the manner in which provision is made for securing a uniform distribution of heat over the entire surface of the wall; the manner in which a portion of the waste heat is recovered and returned to the walls; and other features of construction.

Owing to the relatively large size of coke oven heating walls the temperature of heating gases falls as said gases travel through the walls. Consequently unless special provision is made for insuring a uniform heating action it will be found that by the time the heating gases have fully traversed the walls they will have become cooled to such an extent that an unequal heating effect will be produced. Consequently special provision must be made for compensating the delivery of heat from the gases to the walls in order to obtain a substantially uniform heating effect at all points.

In order to secure the most satisfactory operation of the ovens for the recovery of a maximum portion of the by-products it is very desirable to introduce the heating gases initially in the upper portion of the walls, said gas then traveling through the walls downward to a point of delivery adjacent to the lower portion or sole of the oven. It follows that when such an arrangement is used the sole or lower portion of the oven will be relatively cool and consequently the coke will be either imperfectly formed in that portion of the retort or else an undesirably long time will be necessary in order to carry the operation through to a proper termination.

One of the features of the present inven-

tion has reference to the provision of a construction such that practically the entire surface of the walls can be uniformly heated, particularly in that type oven in which the heating gases travel downwardly from top to bottom of the walls. More particularly another object of the invention is to secure the foregoing result within that type of oven in which the heating walls are built up from a series or mesh-work of inter-connected zigzag passages of such form as insure a maximum abstraction or removal of heat from the gases.

Another feature of the invention has reference to the provision of a construction such that the heating effect may be controlled as to secure a practically uniform coking action throughout the entire area of the retort walls. In this connection I will state that in the ordinary horizontal retort oven heated on its side walls it is customary to provide a door at each end of this retort, which doors are normally closed during the coking period. After the coking operation has been completed the doors are removed and the coke is "pushed" by the use of a special pusher appliance which enters through one door and causes the coke to travel out and to be delivered through the other door. In order to facilitate this pushing operation the width of the retort should taper slightly in the direction of the coke pusher, the retort being wider on the coke delivery end than on the pusher end. Since the coke operation commences at the surface of the walls and travels towards the center of the mass in the retort it follows that under ordinary circumstances a greater length of time would be necessary for the coking operation to fully penetrate the coal at the coke end than at the pusher end. This would mean either that the total coking period should be sufficiently longer to insure a complete coking at the coke or wide end of the retort, such interval of time being greater than necessary for the completion of the operation at the pusher end; or that if the coke were to be pushed

as soon as the coking operation had come to a conclusion at the pusher end it would be found that the coking process was not complete at the coke delivery end.

- 5 One of the objects of the present invention is to provide a construction of oven such that the heating effect at different portions of the wall can be controlled independently, and particularly to provide a 10 construction or arrangement in that type of oven in which the width of the retort varies so as to facilitate the pushing operation.

Still another object of the invention is to make provision for securing the aforementioned control in the heating effect in that type of coke oven in which there is provided a mesh-work of inter-connected passages as distinguished from the flue type of oven.

- 20 Still another object of the invention is to greatly improve the construction and operation of the recuperating mechanism when the same is used, so as to secure a very large recovery of waste heat from the spent gases. 25 In this connection still another object is to utilize the arrangement in the sense of making provision for the unit operating of the heating walls of each oven in conjunction with its particular heat recovering mechanism.

30 Other objects and uses of the invention will appear from a detailed description of the same, which consists in the features of construction and combinations of parts hereinafter described and claimed.

- 35 In the drawings Fig. 1 shows a vertical longitudinal section through a retort and the heat recovering mechanism embodying certain of the features of the present invention. It may also be considered as a 40 section taken on line 1-1 of Figs. 3, 4 and 5 looking in the direction of the arrows.

45 Fig. 2 shows a vertical longitudinal section similar to that of Fig. 1 with the exception that it is taken through one of the heating walls and shows the gas passages within the same. It may also be considered as a section taken on the line 2-2 of Figs. 3, 4 and 5 looking in the direction of the arrows.

50 Fig. 3 is a vertical cross-section taken on the line 3-3 of Fig. 2 looking in the direction of the arrows;

55 Fig. 4 is a vertical cross-section on the line 4-4 of Fig. 2 looking in the direction of the arrows;

60 Fig. 5 is a vertical cross-section taken on the line 5-5 of Fig. 2 looking in the direction of the arrows;

65 Fig. 6 shows a vertical cross-section taken on the line 6-6 of Fig. 2 looking in the direction of the arrows;

Fig. 7 shows a longitudinal section taken on the line 7-7 of Fig. 4 looking in the direction of the arrows;

Fig. 8 shows a longitudinal section taken on the line 8-8 of Fig. 5 looking in the direction of the arrows;

Fig. 9 is a horizontal section taken on the line 9-9 of Fig. 4; 70

Fig. 10 is a horizontal section taken on the line 10-10 of Figs. 3, 4, 5 and 6;

Fig. 11 is a horizontal section taken on the line 11-11 of Figs. 3, 4, 5 and 6;

Fig. 12 is a horizontal section taken on the line 12-12 of Figs. 3, 4, 5 and 6; 75

Fig. 13 is a horizontal section taken on the line 13-13 of Figs. 3, 4, 5 and 6;

Fig. 14 is a horizontal section taken on the line 14-14 of Figs. 3, 4, 5 and 6; 80

Fig. 15 is a horizontal section taken on the line 15-15 of Figs. 3, 4, 5 and 6;

Fig. 16 is a horizontal section taken on the line 16-16 of Figs. 3, 4, 5 and 6; 85

Figs. 13, 14, 15 and 16 may also be considered taken on the lines 13-13, 14-14, 15-15 and 16-16 of Fig. 1 looking in the direction of the arrow; and

Fig. 17 is a typical diagrammatic view of a pipe arrangement for controlling the 90 delivery of gas to both sets of burners.

I will first describe in detail the coke oven constructions disclosed herein and will afterwards explain in detail the particular construction of heat recovering devices which 95 are illustrated.

Each oven or retort is provided with a pair of heating walls 20 and 21. On the interior of each wall is a series of gas passages for the accommodation of the heating 100 gases. For certain purposes it is desirable to provide an arrangement in which the heating gases travel downwardly through the passages of the wall, combustion commencing at the top, and the spent gases being 105 withdrawn from the bottom portion of each wall. Among other reasons why this is a desirable arrangement may be stated the fact that it is thus possible to operate the oven with a relatively cool dome or upper 110 portion, and it is also possible to maintain the sole of the oven more easily at the proper temperature. For this reason I have shown a construction in which the heating gases travel downwardly through the passages. 115

I may also state at this point that in many cases it is desirable to use a construction of heating wall having a mesh-work of interconnected gas passages as distinguished from a construction in which the gases travel through independent flues. This type of arrangement facilitates and improves the transfer of heat into the walls and correspondingly improves the operating efficiency 120 and the ability to accurately control temperatures. I have therefore illustrated that type of heating wall which is built up from notched blocks according to the principle included in Letters Patent of the 125 130

United States, Number 1,132,685 issued to me March 23, 1915, for improvements in coke ovens and the like, but I wish it distinctly understood that in illustrating this type of heating wall construction I do not thereby intend to limit myself to its use in conjunction with the features of the present invention except as I may limit myself in the claims.

10 Referring particularly to Figs. 9 to 16, inclusive, it will be observed that the retort or carbonizing chamber 22 varies in width between the doors 23 and 24, being wider adjacent to the door 24 than adjacent to the door 23. In the pushing operation the pusher advances through the opening of the door 23 and the coke is delivered through the opening of the door 24. The door 23 is located at the pusher end and the door 24 at the coke end. This tapering in the width of the oven or retort facilitates the discharge of the coke and thereby greatly improves the operation of the oven.

As previously explained, the coking operation would normally reach its termination sooner at the narrow end than at the wide end of the oven. In order to compensate for this tendency I have provided means for controlling the heat at different portions 30 of the wall so as to make it possible to equalize the coking time in all portions of the retort. In the particular construction illustrated this control is secured in the following manner: A series of burners 25 is located throughout the length of the upper portion of each heating wall. These burners receive their gas for combustion through independent control valves 26, and by opening the control valves different amounts in 40 different portions of the wall it is possible to secure the compensation or equalization previously explained.

In those cases in which independent control valves are used for the various burners in a coke oven of varying width and in which the heating gases travel through independent flues it will be evident that the heating effect at each portion of the wall may be very accurately regulated independently of the other portions of the wall because there will be assurance that the heating gases delivered by the various burners will follow the courses prescribed by their respective flues. I contemplate as being within the scope of the present invention such arrangements when used in conjunction with retorts of varying width.

In the particular type of the heating wall illustrated in the drawings of the present case there is a meshwork of independent passages so that it is evident that the heating gases are allowed to interchange or exchange more or less freely between different portions of the wall and consequently in some cases it might be found that owing

to local conditions the temperatures in the different portions of the wall would not accurately follow the adjustments of the various burners. In order to compensate for such a possibility I have provided as shown particularly in Fig. 2 a number of vertical partitions or baffles 27, 28, 29 and 30 on the interior of each heating wall which baffles divide the total length of the wall into sections or zones more or less isolated from each other, although in each of said sections there is a meshwork of interconnected passages within which transfer or exchange may take place. It will therefore be evident that the use of such partitions or such sectioning arrangement bears in some cases a peculiar relationship to the independent control of temperatures at different portions of the heating wall in those ovens in which the width is not uniform throughout the length of the retort. In this connection I wish to state that in my co-pending application for Letters Patent of the United States on improvements in regenerative coke ovens, Serial Number 105,133, filed June 22, 1916, and renewed November 8, 1918, as Serial Number 261,740, I have shown a construction of a heating wall having on its interior a meshwork of interconnected passages and I have also shown in that case the use of a series of partitions or baffles for dividing the entire length of the meshwork of passages into a series of zones or sections. However, I have not shown the said arrangement in said application as used in conjunction with in a retort of varying width, nor have I claimed said construction in said case, having reserved the same for claims in this application.

Considering the construction of the heating wall more in detail it will be observed that adjacent to each of the burners 25 is a vertical inspection port or capacity 31 leading from the upper surface of the heating wall downwardly to a chamber 32 adjacent to the lower end of the corresponding burner. Air for combustion is admitted to the chambers 32 and passes from them down through ports 33 which lead into the combustion chambers 34 beneath the several burners. The nozzles or burners discharge their gas directly into these combustion chambers where same mixes with the air delivered through ports 33 and combustion commences at this point.

Above each of the ports 33 will be observed a block 35 slidably mounted within the corresponding chamber 32. By introducing rods or other tools through the inspection ports 31 it will be possible to manipulate the blocks 35 into such position as to more or less completely cover the corresponding air ports 33 and in this way the delivery of air to each combustion chamber may be controlled independently of the

other chambers. Since the amount of air delivered has a direct bearing on the combustion it will be observed that these inspection ports and the air control blocks are also used for independently controlling the temperature at different portions of the wall. It is therefore possible to control both of the constituents of combustion locally at various points in the wall.

10 Referring particularly to Figs. 4, 10, 11, 12, 13 and 14, there will be observed a series of vertically extending passages 36 in each partition wall, there being a group of passages in each partition wall corresponding to each of the adjacent heating walls. The air for combustion rises through these passages and is thereby delivered to the chambers 32 previously mentioned. In the particular construction illustrated these passages 36 receive their air into their lower ends from a recuperator structure in the foundation of the bench of ovens, but it will be apparent that as far as the delivery of air to the heating walls is concerned the recuperator structure might be dispensed with or other heat recovery devices substituted. The passages 36 for the air delivery to each heating wall are shown as being quite independent of corresponding passages for the other heating wall.

15 Examining Figs. 3, 4, 5 and 6, there will be observed a pair of longitudinally extending passages 38 and 39 joining together the lower portions of all of the passages 36 for each heating wall. These passages or channels 38 and 39 serve to equalize the air received from the different portions of the recuperator structure presently to be described and thereby equalize the preheating effect on the air for all portions of the wall. Furthermore, if there should be more of a demand for air adjacent to some burners than adjacent to other burners the air flow can be equalized in the lower portion of the structure by these passages or channels 38 and 39.

20 The spent gases are delivered from the lower portion of the heating walls of each oven into a common channel or tunnel 40 beneath the sole of said oven. This channel or tunnel should be of sufficient cross-sectional area to carry the entire volume of gases delivered without being overloaded. It is, however, desirable to make it as narrow as possible so that the load of the material in the carbonizing channel can be transmitted as directly as possible into the foundation through the supporting walls 41 and 42. For this reason I have shown the said channel 40 as tapering in width, being narrower in its top portion than in its bottom portion.

25 The channel 40 extends throughout the entire length of the oven as shown particularly in Figs. 1 and 2. Beneath it is a pair

of shorter channels 43 and 44 each of which is of approximately one-half the length of the oven, said channels being separated by a partition 45. Communicating with the outer ends of the channels 43 and 44 are the downcomers or ports 46 and 47 respectively.

30 Beneath each retort is a pair of heat recovering structures 48 and 49 which in the construction illustrated take the form of recuperators. The recuperator 48 handles the spent gas from the channel 43 and the recuperator 49 handles the spent gas from the channel 44.

The recuperator structures 48 and 49 are separated by a centrally located partition 50 as shown in Fig. 1.

35 The recuperators herein disclosed are built up from tiles or flues, such as 51, set end to end but separated at intervals by horizontal spacer blocks 52 and vertical spacer blocks 53. Each recuperator comprises two sets of such tiles or flues in each layer as shown in Figs. 3, 4, 5 and 6, and the vertical spacer blocks 53 are set alternately between the tiles of a layer and at the sides of the tiles of the next layer. There is thus provided a series of passages between the tiles extending in zigzag fashion upwards around the tiles from the lower portion to the upper portion of the structure.

40 Suitable blocks 54 serve to close the spaces between the end portions of the tiles as clearly shown in Fig. 1, thereby preventing any transfer of air or gas between the interiors of the tiles and the spaces around them. Horizontal partitions 54', 55 and 56 are provided adjacent to certain of the end tiles so as to establish spaces 57, 58 and 59 adjacent to the tile openings at one end of the structure and other spaces 60 and 61 adjacent to the tile openings at the other end of the structure. The arrangement is such that spent gases descending through the downcomer 46 travel towards the center of the structure through the upper layers of tiles, back towards the end of the structure through the next lower layers of tiles, again towards the center of the structure through the next layers of tiles, and finally to the discharge connection 59 through the lowermost layers of tiles.

45 In the particular arrangement illustrated there are three layers of tiles back and forth in the upper two passages, but only two layers of tiles back and forth in the lower two passages. As the spent gases traverse the recuperator structure their temperature is lowered and their volume correspondingly diminished. It is therefore unnecessary to provide as large cross-sectional area for spent gases in the discharge side of the recuperator as on the intake side thereof, and for this reason I have illustrated the relationship of tile passages just explained.

- The discharge connection 59 at each end of the structure connects to a suitable tunnel or other gas receiving arrangement under the control of a damper 62 if desired so that 5 the draft on different portions of the structure can be equalized. In this connection it is observed that between the sole passage or channel 40 and the corresponding channels or passages 43 and 44 is a series of ports 63 10 above which are the draft control blocks 64. These latter may be manipulated by rods or other implements introduced through inspection ports 65 when the same are uncovered, and it is thus possible to equalize 15 the draft on different portions of channel 40. This is a very desirable feature for the reason that said channel is of considerable length and gathers the spent gases from the entire length of the heating wall so that 20 unless special provision was made for controlling the draft at different points in its length it might be found that there would be more draft in some portions of the heating walls than on others.
- 25 The zigzag air passages previously described as being formed around the outer surfaces of the tiles communicate at the lower ends with the longitudinal channels 66 and 67 under the two halves of the recuperator structure. These channels receive air through the connection 68 from any suitable source such as a blower or the like and under control of the blocks or dampers 69 which may be manipulated through the 30 inspection ports 70 when said ports have been uncovered.
- At their upper ends the zigzag air passages communicate with the lower ends of the air risers 36 as will be clearly understood from examination particularly of Figs. 1 and 4. In order to equalize the heated air independently before it enters the risers 36 I have shown a pair of longitudinally extending channels 71 and 72 just 40 above each recuperator. These channels extend the full length of both recuperators as shown in Fig. 1 and thus serve not only to equalize the heated air from both recuperators but also serve to deliver the necessary portion of such preheated air to the risers 36 in the central portion of the heating walls. As shown in Fig. 1 several of these risers are located above the partition 45 50 and would therefore not receive a proper supply of air unless side connections were provided such as the channels 71 and 72.
- It was previously mentioned that as the heating gases traverse the walls their temperature falls owing to the loss of heat from them. This loss of temperature will in some cases be so large that it will be desirable to make special provision for compensating the heating effect. I will now describe the construction illustrated herein for making 55 such provision.

The full quantity of air of combustion is initially introduced into the chambers 32 but only a portion of the gas for combustion is initially introduced through the burners 25. Consequently the air will be 70 only partially consumed and there will remain in the products of combustion a considerable portion of free oxygen. Ordinarily 50 or 60% of the total gas for combustion will be initially introduced through the burners 25, 100% of air having been introduced, and consequently there will remain approximately one-half of the oxygen unconsumed. The excess portion of air as compared to gas will serve also to temper 80 the combustion so that the heat will be generated at a relatively lower temperature and with less danger of burning the structure. It will also be observed in this connection that there will be a greater total 85 volume of gases than would ordinarily be present for the combustion of the initially introduced fuel gas, and therefore the gas passages in the upper portions of the heating walls will be correspondingly crowded 90 and there will be better assurance that the burning mixture will uniformly and evenly fill all portions of the meshwork of passages.

As the gases travel downwardly they move 95 through the upper courses of the meshwork of passages and give up a portion of their heat. After the wall has been partially traversed the gases encounter additional or supplemental ports 73 through which the 100 remaining quantity of the gas for combustion is introduced. These ports 73 are formed in blocks 74 which extend over into the partition wall and communicate with supplemental gas passages 75 which extend 105 down through the upper portion of said wall. These supplemental gas passages are under the control of valves 76 at the upper portion of the structure so that the amount of supplemental gas introduced at each supplemental burner can be controlled independently of the other burners.

It will be observed that the large blocks 74 in which are formed these supplemental burners 74, while lapping over a portion of the partition wall do not prevent independent expansion or contraction of the heating walls as compared to the partition wall since planes of shear are established on the upper and lower surfaces of the blocks 74. It will 115 also be observed that by the use of the enlarged blocks 74 it is possible to establish the desired communication between the supplemental ports 73 and the supplemental gas passages 75 while at the same time permitting the parts to adjust themselves independently under expansion and contraction without breaking the continuity of the passages.

I wish to point out that in my co-pending 130

application for Letters Patent of the United States on improvements in the art of heating walls, Serial Number 201,112, filed November 9, 1917, I have disclosed a type 5 of heating wall construction in which provision is made for the introduction of a supplemental portion of gas for the purpose of reinforcing combustion.

Referring particularly to Fig. 17, the 10 same shows diagrammatically a simple arrangement of piping for supplying gas under control to the various groups of burners in the individual heating walls. Above each 15 pair of heating walls is located four gas pipes, 77, 78, 79 and 80, the pipes being connected to their respective groups of burners under control of individual valves.

While I have herein shown and described 20 only a single embodiment of the features of my present invention still I do not limit myself to said embodiment except as I may do so in the claims.

I claim:

1. In a coke oven structure, the combination 25 of a pair of vertical heating walls providing a distillation retort between them, each of said heating walls having on its interior a meshwork of inter-connected passages for heating gases extending in zigzag 30 fashion downwardly through the wall, a series of burners located throughout the length of the upper portion of the wall, air chambers adjacent to said burners, there being vertical inspection openings leading 35 to said air chambers, connections from the air chambers to the heating passages, dampers in the chambers for the control of said connections, said dampers being located in position for adjustment through said inspection 40 openings, means for collecting spent gas from all portions of the lower edge of each heating wall, heat recovering devices having horizontally extending passages for spent gases extending in zigzag fashion 45 therethrough, and connections for the delivery of air from said heat recovering devices to the air chambers aforesaid, substantially as described.

2. In a coke oven structure, the combination 50 of a pair of heating walls providing a retort between them, there being a series of downwardly extending passages for heating gases in each of said walls, a series of burners for introducing gas for combustion 55 into said passages, a series of air chambers in the upper portion of each heating wall, there being a vertically extending inspection opening above each air chamber, offset connections for delivering air to said chambers, 60 connections for the delivery of air from each air chamber into the heating gas passages aforesaid, dampers located in said chambers for manipulation through said inspection 65 openings for the control of air delivery through said ports, means for collecting

spent gas from all portions of the heating walls for delivery at the end portions of the oven, and heat recovering devices in conjunction with the aforesaid structures and including spent gas passages extending horizontally 70 from said connections towards the center of the structure and horizontally from the center of the structure towards a point of discharge, and air passages in conjunction therewith for the delivery of air 75 from points adjacent to said spent gas passages to said air chambers aforesaid, substantially as described.

3. In a bench of coke ovens, the combination 80 of a series of retorts located adjacent to each other, each retort having a pair of side heating walls, each heating wall having on its interior suitable passages for the transfer of heating gases downwardly therethrough, means for introducing gas into 85 the heating passages of each wall independently of the other walls, heat recovering devices beneath each oven independently of the other ovens, connections for the delivery 90 of spent gas from the walls of each oven to the heat recovering devices for that oven independently of the other ovens, and connections for the delivery of air for combustion from the heat recovering devices of each oven independently of the other ovens, substantially 95 as described.

4. In a bench of coke ovens, the combination 100 of a series of retorts located adjacent to each other, heating walls for each retort, heat recovering devices for each oven and the heating walls thereof independently of the other ovens, connections for the delivery 105 of spent gas from the walls of each oven to the heat recovering devices thereof independently of the other ovens, and connections for the delivery of air from the heat recovering devices of each oven independently of the other ovens, substantially as described.

5. In a bench of coke ovens, the combination 110 of a series of retorts located in close proximity to each other, heating walls for each retort independently of the other retorts, heat recovering devices located beneath each retort and the heating walls 115 thereof, spent gas passages in each of said heat recovering devices and independent of the other heat recovering devices, air passages in each of said heat recovering devices and independent of the other heat recovering devices, connections for the delivery of spent gas from the walls of each oven only to the spent gas passages of the corresponding heat recovering devices, and connections 120 for the delivery of air from the air passages only of said heat recovering devices to the corresponding heating walls, substantially as described.

6. In a coke oven, the combination of a 125 pair of heating walls comprising notched

blocks set together to provide a meshwork of inter-connected passages for heating gases, partitions within each wall dividing said passages into a series of vertical zones, 5 and means for delivering gas and air into the passages of the different zones under control and independently of the other zones, to thereby locally regulate the temperatures of the heating walls, the heating 10 walls being farther apart at one end of the structure than at the other end, substantially as described.

7. In a bench of coke ovens, the combination of a series of retorts located in close 15 proximity to each other, a foundation on which said retorts are carried, heating walls for each retort, partition walls in the foundation beneath the heating walls of consecutive ovens, heat recovering devices for 20 each oven between a pair of said foundation partition walls, and means for collecting spent gas from the heating walls of each oven independently of the heating walls of the other ovens comprising a sole channel 25 beneath each oven narrow in its upper portion and broad in its lower portion, and means for transferring spent gas between the sole passage of each oven and the corresponding heat recovering devices, substantially 30 as described.

8. A coke oven structure comprising in combination a retort having a pair of heating walls, passages for heating gases in each wall, heat recovering devices beneath each 35 oven independently of the other ovens, means for transferring spent gas from the heating walls of each oven to the corresponding heat recovering devices, means for transferring from the heat recovering devices to the 40 upper portions of the heating walls of the oven a full quantity of air for combustion, means for introducing a partial quantity of gas for combustion into the upper portion of the heating passages of said walls, and 45 means for introducing a supplemental portion of gas for combustion to the central portions of the heating walls of said oven, substantially as described.

9. In a coke oven, the combination of a 50 pair of heating walls each having on its interior a series of vertically extending groups of interconnected passages for heating gases within each of which the descending gases are free to intercommunicate, said groups 55 of passages being isolated from each other in their body portions whereby gases in one group are prevented from interchange with the gases of the other groups, the inner faces of the heating walls providing the 60 sides of the chamber, said sides being closer together at one end of the chamber than at the other end therof, and means for introducing combustible constituents into the upper ends of the groups independently of 65 each other and under control, whereby the

heating effect within the walls may be controlled at various points independently of other points, substantially as described.

10. In a coke oven, the combination of a pair of heating walls each having on its interior a series of interconnected passages extending in zig-zag fashion from its upper to its lower portion, vertically extending partitions within each wall serving to divide the same into a series of isolated groups 70 of passages within each of which the gases are free to transfer laterally while prevented from interchange between the groups of passages, the inner faces of the walls providing the sides of the chamber, said sides being 75 closer together at one end of the chamber than at the other end thereof, and means for introducing combustible constituents into the upper end of each group of passages independently of the other groups, whereby the 80 heating effect at various points throughout the length of the walls may be independently controlled to thereby compensate for the unequal width of the chamber, and whereby the 85 gases are free to interchange within the 90 passages of each of said groups, substantially as described.

11. In a coke oven, the combination of a pair of heating walls each having on its interior a series of interconnected passages extending in zig-zag fashion from its upper to its lower portion, the inner faces of said walls providing the sides of the chamber, said sides being closed together at one end of the chamber than at the other end thereof, means for introducing combustible constituents into the upper ends of the walls, and means under the control of the operator for varying the introduction of said combustible constituents at different portions of the walls independently of other portions, to thereby compensate in heating effect for the decreased width of the oven at one end as compared to the other end, substantially 100 as described.

12. In a bench of coke ovens, the combination of a series of retorts located in close proximity to each other, a foundation on which said retorts are carried, heating walls for each retort, partition walls in the foundation beneath the heating walls of consecutive retorts, heat recovering devices for each oven between a pair of said foundation partition walls, and means for collecting spent gas from the heating walls of each oven independently of the heating walls of the other ovens comprising a sole channel beneath each oven, and means for transferring spent gas between the sole passage of each oven and the corresponding heat recovering 105 devices, substantially as described.

13. In a coke oven, the combination of a pair of heating walls each having on its interior a meshwork of interconnected passages for heating gases extending in a gen- 110

erally vertical fashion through the walls, partitions within each wall serving to divide the passages thereof into a series of independent groups constituting vertical zones, and means for delivering gas and air into the upper portions of the groups of passages independently of the other groups to thereby locally regulate the temperatures of the heating walls, substantially as described.

14. In a coke oven a heating wall having on its interior a series of interconnected passages constituting a meshwork extending in a generally vertical direction from its upper to its lower portion, there being a series of combustion chambers in the upper portion of the wall having their lower ends in communication with said meshwork, a gas nozzle terminating in the upper end of each such combustion chamber and delivering gas thereto, an air port at each side of each nozzle aforesaid having its lower end delivering air into the said combustion chamber, there being inspection ports in vertical alignment with said air ports, and an adjustment block above the upper end of each such air port and in vertical alignment with an inspection port, substantially as described.

15. In a coke oven a heating wall having on its interior a series of vertically extending passages for the transfer of heating gases, there being a series of combustion chambers in the upper portion of the heating wall having their lower ends in communication with the upper portion of the said vertically extending passages, a gas nozzle terminating in the upper portion of each said combustion chamber, an air port at each side of each said nozzle, an inspection port in vertical alignment with each said air port, and an adjustment block in position adjacent to the upper end of each said air port and adjustable through the inspection port aforesaid, substantially as described.

16. In a coke oven a heating wall having on its interior a series of vertically extending passages for the transfer of heating gases, there being a series of combustion chambers in the upper portion of the wall having their lower ends in communication with the upper portions of the passages aforesaid, a gas nozzle communicating with each said combustion chamber, an air port at each side of each gas nozzle, an inspection port in vertical alignment with each said air port, and an adjustment block in position adjacent to the upper end of each said air port and in vertical alignment with the corresponding inspection port, substantially as described.

17. In a coke oven a heating wall having on its interior a series of vertically extending passages for the transfer of heating

gases, there being a series of combustion chambers in the upper portion of the wall having their lower portions in communication with the upper portion of the heating gas passages aforesaid, a gas connection terminating in each of said combustion chambers, an air port at each side of each such gas connection, an adjustment block adjacent to the upper end of each such air port, and an inspection opening in vertical alignment with each such adjustment block and adjustable therethrough, substantially as described.

18. In a coke oven a heating wall having on its interior a series of vertically extending passages for the transfer of heating gases, a series of gas connections in communication with the upper portion of said passages and delivering gas, an air port at each side of each such gas connection, an adjustment block adjacent to the upper end of each such air port, and an inspection port in vertical alignment with each such adjustment block and adjustable therethrough, substantially as described.

19. In a coke oven a heating wall having on its interior a series of passages for the transfer of heating gases in a vertical direction, a series of gas connections in communication with the upper portions of said passages, an air port adjacent to each such gas connection, an adjustment block adjacent to each such air port, and an inspection port in vertical alignment with each such adjustment block and adjustable therethrough, substantially as described.

20. In a coke oven a heating wall having on its interior a series of heating passages for the transfer of heating gases in a vertical direction, means for delivering combustible mixture into the upper portion of said wall with one of the constituents of combustion in excess of the other, means for removing spent gas from the lower edge of the wall, and a series of blocks extending through the central portion of the wall in horizontal alignment with each other and on a plane of shear, each such block having on its interior a passage for the transfer of gas to the interior portion of the heating wall passages, and means for delivering gas to the passages of said blocks, substantially as described.

21. In a coke oven a heating wall having on its interior a series of passages for the transfer of heating gas in a vertical direction, said wall comprising courses of blocks, means for introducing combustible constituents into the upper portion of the wall, and a course of blocks in the central portion of the wall lying in a plane of shear, each such block having on its interior a transversely extending passage having its inner end in communication with the passages of the wall, and having its outer end in

communication with a vertical passage, substantially as described.

22. In a coke oven a heating wall having on its interior a series of vertically extending passages for heating gases, said wall comprising courses of blocks, means for introducing combustible constituents into the upper portion of said wall, and a course of blocks in the central portion of the wall 5 lying in a plane of shear, selected ones of said blocks having transversely extending passages with their inner ends in communication with the passages in the interior of the wall, substantially as described.
23. In a coke oven a heating wall having on its interior a series of vertically extending passages for the transfer of heating gases in a vertical direction, a horizontally extending series of blocks in the central portion 10 of the wall lying in a plane of shear, each such block having on its interior a transversely extending passage with its inner end in communication with the heating gas passages, and means for delivering 15 combustible constituent to the outer end of each transversely extending passage, substantially as described.
24. In a coke oven a heating wall having on its interior a series of vertically extending 20 passages for the transfer of heating gases in a vertical direction, a series of blocks in the central portion of the wall located in vertical alignment in a plane of shear, selected ones of said blocks having 25 transversely extending transfer passages with their inner ends in communication with the heating gas passages aforesaid, and means for introducing combustible constituent into the outer ends of the transfer 30 passages aforesaid, substantially as described.
25. In a coke oven a heating wall having on its interior gas transferring passages for the transfer of heating gases in a vertical 35 direction, means for introducing constituents of combustion into the upper portions of said passages, a series of blocks in the central portion of the wall lying in a plane of shear and having their inner ends 40 overlying the passages for heating gases, and having their outer ends projecting beyond the outer face of the wall, and transfer passages in selected ones of said blocks having their inner ends in communication 45 with the heating gas passages, and their outer ends in position for the reception of combustible constituent, substantially as described.
26. In a coke oven a heating wall having 50 on its interior gas transferring passages for

the transfer of heating gases in a vertical direction, means for introducing combustible constituents into said passages adjacent to one edge of the wall, a series of blocks in the central portion of the wall 55 lying in a plane of shear and having their inner ends overlying the heating gas passages, and having their outer ends projecting beyond the outer face of the wall, and transfer passages in selected ones of 60 said blocks having their inner ends in communication with the heating gas passages, and their outer ends in position for the reception of combustible constituent, substantially as described. 75

27. In a coke oven the combination of two heating walls each having on its interior a series of passages for the transfer of heating gases from its upper to its lower edge, a common sole passage beneath the sole of 80 the oven and in communication with the lower edges of the passages of both walls, said sole passage extending the full length of the sole of the oven, a spent gas passage beneath each end of said sole passage, a 85 series of openings between the sole passage and each such spent gas passage, heat recovering devices beneath each such spent gas passage, and a connection from the outer end of each spent gas passage to the corresponding heat recovering device, substantially as described. 90

28. In a coke oven the combination of two heating walls each having on its interior a series of passages for the transfer of heating gases from its upper to its lower edge, a common sole passage beneath the sole of the oven and in communication with the lower portions of the heating passages of 95 both walls, means adjacent to each end of the oven for the reception of spent gas from the adjacent portion of the sole passage, and heat recovering devices in conjunction with each such receiving means, substantially as described. 100

29. In a coke oven the combination of two heating walls each having on its interior a series of passages for the transfer of heating gases from its upper to its lower edge, a common passage for the collection of all 110 the spent gases from the lower edges of both said walls, heat recovery devices in conjunction with said heating walls and no other heating walls, and connections from the collection passage aforesaid to said heat recovery devices, substantially as described. 115
